UNITED STATES PATENT OFFICE.

JOHN R. HAMILTON, OF YONKERS, NEW YORK, ASSIGNOR TO VENTURI ALARM COMPANY, OF DOVER, NEW JERSEY, A CORPORATION OF NEW JERSEY.

SPRINKLER-ALARM APPARATUS.

1,026,439.

Specification of Letters Patent.

Patented May 14, 1912.

Application filed June 26, 1909. Serial No. 504,423.

To all whom it may concern:

Be it known that I, JOHN R. HAMILTON, a citizen of the United States, and resident of Yonkers, county of Westchester, and 5 State of New York, have made a certain new and useful Invention Relating to Sprinkler-Alarm Apparatus, of which the following is a specification, taken in connection with the accompanying drawing.

10 This invention relates to sprinkler alarm apparatus and relates especially to apparatus in which the alarm is provided with alarm valves or actuating devices normally operating the alarm on a relative decrease 15 in pressure in the distributing system and also provided with detent devices which are operated on an initial increase of pressure in the supply pipe so as to prevent the operation of the alarm devices.

20 In the accompanying drawings, showing in a somewhat diagrammatic manner an illustrative embodiment of this invention, and in which the same reference numeral refers to similar parts in the several figures, 25 Figure 1 is a diagrammatic elevation, parts being shown in section, and Fig. 2 is an enlarged section of part of the device.

As indicated the supply pipe 1 may be connected with suitable distributing pipes, 30 such as 38, at the various floors 40 of the building so as to supply sprinkler heads, such as 39, located at intervals in the usual manner. The main 5 may connect through the suitable shut-off valve 4 with the inlet 35 portion 3 of the supply pipe leading to the supply chamber 80 which may have a suitable supply valve in the form of a check valve 81 coöperating if desired with a valve seat 61 having an annular recess communicating with the vent or drip connection 33 leading to the drip chamber 43 so as to relieve the pressure in this annular recess and give the valve a differential action. The drip chamber may as indicated be provided 40 with a drip ball 45 mounted upon a suitable contact lever 48 so that when the leakage cannot be taken care of through the escape pipe 50 having a suitably throttled discharge the drip ball rises and the lever 45 comes in contact with the coöperating contact 44 in the insulating bushing 49 so as

to complete the electric circuit indicated through the battery 46 and drip alarm 47 calling attention to this difficulty. A similar distributing valve may be mounted at 55 the other side of the supply chamber next the distributing system, or if desired, the distributing valve 30 may be loosely mounted on the valve lever 32 and as indicated may have the bleeding passage which should 60 be of such size as to properly coöperate with the bleeding passage 74 in the supply valve, in the form of a Venturi passage 34, as is indicated in somewhat greater detail in Fig. 2. The exhaust passage 62 may, 65 as indicated, communicate with the throat of the venturi and with the annular recess 35 in the valve seat 60, so that as flow commences the reduction of pressure at the throat of the venturi causes a corresponding 70 reduction of pressure in the annular recess in the valve seat which may be given the proper size to effect the desired differential action of the valve. If desired a suitable air chamber 37 may be connected with the 75 supply chamber by the pipe 36 preferably provided with a suitable adjusting valve 56 so as to regulate the flow of fluid during operating conditions.

The alarm apparatus may comprise a suitable float chamber 8 and coöperating detent chamber 7 connected by a suitable channel, such as 52, which may be provided with a suitable detent valve seat 66. This chamber may have a suitable valve seat 68 with which 80 the float or alarm valve 69 coöperates so as to control the action of the alarm devices and the float valve may, as indicated, be loosely connected with a suitable float 9 in the float chamber which may, as indicated, 85 be provided with a suitable stem 16 on which is mounted a suitable socket or connecting member 70 loosely embracing a collar or projection at the lower end of the float valve 69. A suitable buoyant fluid, 90 preferably of a heavy water immiscible character, such for instance, as mercury may be used in the float chamber which may be provided with a suitable choke passage 10 of sufficient length or provided with a sufficient enlargement or reservoir 11 so as to 95 allow the proper action of the fluid, an ad-

justable choke valve 53 being if desired located adjacent the lower portion of this passage so as to adjust its effective area. Similar fluid may be used in the detent chamber and connected throttle passage 51 which may be similarly provided with an adjustable throttle valve 54 so as to control its effective area and the movement of the fluid from the detent chamber into the 10 throttle passage with which a suitable enlargement or receiver 6 may be connected, if desired. It is of course understood that the other parts of these chambers, except the air chamber and drip chamber, and also 15 the supply and distributing pipes are normally filled with water which is not indicated in the drawing to avoid confusion. A suitable detent member 13 may be mounted in any desired way in the detent chamber 20 so as to be buoyed up when the fluid rises therein and this detent member may, as indicated, be loosely pivoted to a suitable bell crank lever or connection 14 connected to the detent 15 which may as indicated be located within the channel 52 and be supported adjacent its free end in a suitable 25 guide 67. This detent may coöperate in any desired way with the alarm valve or connected alarm devices so as to prevent its 30 actuation when the detent is operated. For example, the end of the detent may when it is forced forward engage in a suitable lock connected to the float or float valve, as for example by forming a suitable lock 71 35 in the form of annular notches on the stem 16 of the float valve which may of course be loosely guided in any desired way in its vertical movements. Or if desired a suitable 40 detent valve 65 preferably of a yielding character may be mounted on the detent so as to engage the coöperating detent valve seat 66 when the detent is operated and thus close the connecting channel and in this 45 way prevent the actuation of the alarm valve and devices or, if desired, both these expedients may be adopted as indicated in the drawings.

Any suitable forms of alarm may be used, such for example, as the usual mechanical 50 alarm in the form of a suitable water motor 19 whose shaft carries a bell hammer 22 to engage a bell located on the outside of the building or other desired place, when water is supplied to the motor which may have the 55 discharge pipe 20. A suitable electrical alarm may also be used if desired and this may be in the form of an alarm bell connected with its operating battery or the like and with the two contacts 25, 26 coöperating 60 with the contact member 27 mounted on a suitable flexible diaphragm 29 within the chamber 24. When the pressure in the pipe 23 increases this diaphragm is of course forced upward, making electrical contact 65 through the bell and battery and giving a

suitable alarm. These alarms may as indicated be operated by connecting them with the alarm pipe 18 which is connected with the pocket or discharge head 17 adjacent the valve seat 68 and controlled by the alarm or float valve 69 so that when this valve is withdrawn from its seat fluid within the float chamber may pass to the alarms and actuate them. 70

A suitable distributing connection such as 75 12 may connect the distributing system preferably adjacent the supply chamber with the choke passage 10 or its reservoir 11. A suitable supply chamber connection such as 41 may connect the supply chamber with the 80 detent chamber 7 and channel 52, and also under normal conditions with the float chamber 8. A suitable main connection such as 42 may connect the supply pipe below the supply chamber, that is, on the opposite side from the distributing system with the throttle passage 51 or the connected enlargement thereof, that is, the receiver 6. It will of course be readily understood by those familiar with this art 85 that the emergency operation of the system in the event of a fire causes flow of water from the various sprinkler heads and consequent diminution of pressure in the distributing system and connected supply pipe. This reduction of pressure is transmitted 90 through the distributing connection 12 to the reservoir 11 into which the mercury or other buoyant fluid is forced from the float chamber so that after a short interval the 95 float 9 ceases to press the float valve 69 against its seat and finally withdraws it therefrom allowing the admission of fluid to the alarm pipe 18 and thus actuating the alarms. If, however, an increase of pressure 100 through water hammer or other action occurs in the main and connected portion of the supply pipe below the supply chamber this increase of pressure would be transmitted through the main connection 42 and 105 would force the buoyant fluid into the detent chamber, thus raising the detent member 13 and actuating the detent 15. The detent would thus engage the lock 71 and prevent such movement of the float as would 110 actuate the float valve and also, as indicated, the detent valve 65 would be brought into engagement with the coöperating seat 66 so as to close the channel 52 and thus prevent such movement of fluid therethrough as 115 might actuate the float. While of course flow occurs through the comparatively small bleeding passages 34, 74 in or adjacent to the valves on either side of the supply chamber the pressure in this supply 120 chamber remains substantially constant at the beginning of flow in the system, especially when an air chamber is connected thereto. These bleeding passages however 125 take care of slight variations in pressure 130

and gradually equalize the fluid pressure in the various parts of the system, except, of course, under emergency conditions when the valves open, giving a free passage 5 through the supply chamber and supplying water to the heads opened by the fire.

Having described this invention in connection with a number of illustrative embodiments, devices, proportions and arrangements of parts, to the details of which disclosure the invention is not of course to be limited what is claimed as new and what is desired to be secured by Letters Patent is set forth in the appended claims.

1. In sprinkler alarm apparatus, a supply pipe connected with a distributing system and formed with a supply chamber, a distributing check valve between said supply chamber and said distributing system 10 and a supply check valve governing the inlet of said supply chamber away from said distributing system, an air chamber provided with an adjustable connection communicating with said supply chamber, said distributing and supply valves being provided with bleeding passages and with seats having annular recesses, one of said valves having a Venturi passage therethrough and having the exhaust throat of said Venturi 15 passage connected to the annular recess in the coöperating valve seat and one of said valves having the annular recess in its seat connected to a relief drip chamber to cause a differential action, a float chamber, a coöperating detent chamber, a channel connecting said float chamber and said detent chamber, a 20 reservoir connected to said float chamber through a choke passage provided 25 with an adjustable choke valve adjacent its lower portion, mercury in said float chamber, a float having a float stem and lock and having a float valve loosely connected thereto, electrical and mechanical alarms, an 30 alarm pipe connected with and adapted to actuate said alarms and connected to said float chamber through a valve seat controlled by said float valve, a receiver connected with said detent chamber through a 35 throttle passage having an adjustable throttle valve adjacent its lower portion, mercury in said detent chamber, a detent member mounted in said detent chamber, a detent operatively connected with said detent 40 member and coöperating with said lock to prevent the release of said float valve when said detent member is actuated, a detent valve on said detent coöperating with said detent valve seat in said channel, and 45 closing connection between said detent chamber and said float chamber when said detent member is actuated, a supply chamber connection between said detent chamber and said supply chamber, a distributing connection between said reservoir and said dis-

tributing system normally tending to operate said float valve and alarms when the pressure in said distributing system becomes less than in said supply chamber and a main connection between said receiver and said supply pipe to actuate said detent devices when the pressure in said supply pipe increases beyond that in said supply chamber. 70

2. In sprinkler alarm apparatus, a supply pipe connected with a distributing system and formed with a supply chamber, a distributing valve between said supply chamber and said distributing system and a supply valve governing the inlet of said supply chamber, an air chamber communicating with said supply chamber, said distributing and supply valves being provided with seats having annular recesses, one of said valves having a Venturi passage therethrough and having the exhaust throat of said Venturi 75 passage connected to the annular recess in the coöperating valve seat and one of said valves having an annular recess in its seat provided with a relief connection to cause a differential action, there being bleeding 80 passages provided on both sides of said supply chamber, a float chamber, a coöperating detent chamber, a channel connecting said float chamber and said detent chamber, a choke passage connected with said float 85 chamber and provided with an adjustable choke valve, buoyant fluid in said float chamber, a float having a float stem and lock and having a float valve loosely connected thereto, an alarm connected to 90 said float chamber through a valve seat controlled by said float valve, a throttle passage connected to said detent chamber and having an adjustable throttle valve, buoyant fluid in said detent chamber, a detent 95 member mounted in said detent chamber, a detent operatively connected with said detent member and coöperating with said lock to prevent the release of said float valve when said detent member is actuated, a supply 100 chamber connection between said detent chamber and said supply chamber, a distributing connection between said choke passage and said distributing system normally tending to operate said float valve 105 and alarm when the pressure in said distributing system decreases and a main connection between said throttle passage and said supply pipe to actuate said detent devices when the pressure in said supply pipe 110 increases. 115

3. In sprinkler alarm apparatus, a supply chamber to be connected with a distributing system and with a supply pipe, a distributing valve between said supply chamber and said distributing system and a supply valve governing the inlet of said supply chamber away from said distributing system, an air chamber communicating with said supply chamber, bleeding passages 120 125

on both sides of said supply chamber, a float chamber, a coöperating detent chamber adapted to be connected to said supply chamber, an adjustable choke passage connected to said float chamber and adapted to be connected to said distributing system, buoyant fluid in said float chamber, a float and connected float valve in said float chamber, an alarm connected to said float chamber and actuated when said float valve is withdrawn from its seat, an adjustable throttle passage connected to said detent chamber adapted to be connected with said supply pipe, buoyant fluid in said detent chamber, a detent member mounted in said detent chamber and a detent operatively connected with said detent member and preventing the operation of said float valve when said detent member is actuated.

4. In sprinkler alarm apparatus, a supply chamber to be connected with a distributing system and with a supply pipe, a distributing valve between said supply chamber and said distributing system and a supply valve governing the inlet of said supply chamber away from said distributing system, an air chamber communicating with said supply chamber, a float chamber, a coöperating detent chamber adapted to be connected to said supply chamber, a choke passage connected to said float chamber and adapted to be connected to said distributing system, buoyant fluid in said float chamber, a float and connected float valve in said float chamber, an alarm connected to said float chamber and actuated when said float valve is withdrawn from its seat, a throttle passage connected to said detent chamber adapted to be connected with said supply pipe, buoyant fluid in said detent chamber, a detent member mounted in said detent chamber and a detent operatively connected with said detent member and preventing the operation of said float valve when said detent member is actuated.

5. In sprinkler alarm apparatus, a supply chamber to be connected with a distributing system and with a supply pipe, a distributing valve governing the discharge from said supply chamber to said distributing system, a supply valve governing the entrance of fluid into said supply chamber from said supply pipe, an air chamber to be connected with said supply chamber, a float chamber and a coöperating detent chamber to be connected with said supply chamber, a choke passage connected to said float chamber and adapted to be connected with said distributing system, buoyant fluid in said float chamber, a float in said float chamber, an alarm to be actuated by movement of said float, a throttle passage connected to said detent chamber and adapted to be connected with said supply pipe, buoyant fluid

in said detent chamber, a detent member 65
mounted in said detent chamber and a de-
tent operatively connected with said detent
member and preventing the actuation of
said alarm by said float when said detent
member is actuated. 70

6. In sprinkler alarm apparatus, a supply chamber to be connected with a distributing system and with a supply pipe, an air chamber connected with said supply chamber, a distributing valve governing the discharge of fluid from said supply chamber into said distributing system, a supply valve governing the entrance of fluid into said supply chamber from said supply pipe, normally open bleeding passages on both sides of said supply chamber, a float chamber and a coöperating detent chamber adapted to be connected with said supply chamber, a channel connecting said float chamber and said detent chamber and provided with a detent valve seat, a choke passage connected to said float chamber and adapted to be connected with said distributing system, an alarm, means in said float chamber to actuate said alarm by movement of fluid in said float chamber, a throttle passage connected to said detent chamber and adapted to be connected with said supply pipe, a detent having a detent valve coöperating with said detent valve seat and means in said detent chamber to actuate said detent and prevent the actuation of said alarm. 75 80 85 90 95

7. In sprinkler alarm apparatus, a supply chamber adapted to be connected with a distributing system and with a supply pipe 100 and having means at both its inlet and outlet sides to cause a difference of pressure on the beginning of flow therethrough, an air chamber connected to said supply chamber, an alarm and alarm actuating devices adapted to be connected with said distributing system to actuate said alarm on decrease of pressure in said distributing system, a detent chamber to be connected to said supply chamber, a passage connected with said detent chamber and adapted to be connected to said supply pipe, a detent member in said detent chamber to be actuated on an increase of pressure in said supply pipe and a detent operatively connected with said detent member and preventing the operation of said alarm by said alarm devices when said detent member is actuated. 110 115

8. In sprinkler alarm apparatus, an alarm, and alarm actuating devices adapted to actuate said alarm on decrease of pressure in a distributing system, detent actuating means to be connected with the supply pipe of said distributing system and be operated on an increase of pressure in said supply pipe and a detent operatively connected with said detent actuating means and coöperating with said alarm actuating de- 120
125

- vices to prevent their actuating said alarm when said detent actuating means is operated.
9. In sprinkler alarm apparatus, a supply chamber adapted to be connected with a distributing system and with a supply pipe and having means at both its inlet and outlet sides to cause a difference of pressure on the beginning of flow therethrough, an alarm and alarm actuating devices adapted to be connected with said distributing system to actuate said alarm on decrease of pressure in said distributing system, a detent chamber to be connected to said supply chamber, a passage connected with said detent chamber and adapted to be connected to said supply pipe, a detent member in said detent chamber to be actuated on an increase of pressure in said supply pipe and a detent operatively connected with said detent member and preventing the operation of said alarm by said alarm devices when said detent member is actuated.
10. In sprinkler alarm apparatus, a supply chamber to be connected with a distributing system and with a supply pipe, a distributing valve governing the discharge of fluid from said supply chamber into said distributing system, a supply valve governing the entrance of fluid into said supply chamber from said supply pipe, normally open bleeding passages on both sides of said supply chamber, a float chamber and a co-operating detent chamber adapted to be connected with said supply chamber, a channel connecting said float chamber and said detent chamber and provided with a detent valve seat, a choke passage connected to said float chamber and adapted to be connected with said distributing system, an alarm, means in said float chamber to actuate said alarm by movement of fluid in said float chamber, a throttle passage connected to said detent chamber and adapted to be connected with said supply pipe, a detent having a detent valve co-operating with said detent valve seat and means in said detent chamber to actuate said detent and prevent the actuation of said alarm.
11. In sprinkler alarm apparatus, a supply chamber to be connected with a distributing system and with a supply pipe, a distributing valve governing the discharge from said supply chamber to said distributing system, a supply valve governing the entrance of fluid into said supply chamber from said supply pipe, a float chamber and a co-operating detent chamber to be connected with said supply chamber, a choke passage connected to said float chamber and adapted to be connected with said distributing system, buoyant fluid in said float chamber, a float in said float chamber, an alarm to be actuated by movement of said float, a throttle passage connected to said
- detent chamber and adapted to be connected with said supply pipe, buoyant fluid in said detent chamber, a detent member mounted in said detent chamber and a detent operatively connected with said detent member and preventing the actuation of said alarm by said float when said detent member is actuated.
12. In sprinkler alarm apparatus, a supply chamber to be connected with a distributing system and with a supply pipe, a distributing valve between said supply chamber and said distributing system, a float chamber, a co-operating detent chamber adapted to be connected with said supply chamber, a choke passage connected to said float chamber and adapted to be connected to said distributing system, buoyant fluid in said float chamber, a float and connected float valve in said float chamber, an alarm connected to said float chamber, a detent member mounted in said detent chamber and a detent operatively connected with said detent member and preventing the operation of said float valve when said detent member is actuated.
13. In sprinkler alarm apparatus, a supply chamber to be connected with a distributing system and with a supply pipe, a distributing valve between said supply chamber and said distributing system and a supply valve governing the inlet of said supply chamber away from said distributing system, a float chamber, a co-operating detent chamber adapted to be connected to said supply chamber, a choke passage connected to said float chamber and adapted to be connected to said distributing system, buoyant fluid in said float chamber, a float and connected float valve in said float chamber, an alarm connected to said float chamber and actuated when said float valve is withdrawn from its seat, a throttle passage connected to said detent chamber adapted to be connected with said supply pipe, buoyant fluid in said detent chamber, a detent member mounted in said detent chamber and a detent operatively connected with said detent member and preventing the operation of said float valve when said detent member is actuated.
14. In sprinkler alarm apparatus, an alarm, and alarm actuating devices adapted to actuate said alarm on decrease of pressure in a distributing system, a detent member and detent actuating means to be connected with the supply pipe of said distributing system to actuate said detent member on an increase of pressure in said supply pipe, said detent member co-operating with said alarm actuating devices to prevent the actuation of said alarm when said detent member is actuated.
15. In sprinkler alarm apparatus, alarm actuating devices adapted to operate on a

decrease of pressure in a distributing system, a detent member and detent actuating means adapted to be connected with said distributing system to actuate said detent member on an increase of pressure in said distributing system, said detent member co-operating with said alarm actuating devices

to prevent their operation when said detent member is actuated.
